Khourie and Crew[57] **CLAIM**

The ornamental design for a computer carrying case, as shown and described.

DESCRIPTION

FIG. 1 is a perspective view of a computer carrying case showing our new design;
FIG. 2 is a top plan view thereof;
FIG. 3 is a front elevational view thereof;
FIG. 4 is a right side elevational view thereof;
FIG. 5 is a left side elevational view thereof;
FIG. 6 is a rear elevational view thereof;
FIG. 7 is a bottom plan view thereof; and,
FIG. 8 is a perspective view thereof, in an open position, the laptop computer shown in broken lines for illustrative purposes only.

FIG. 1.

FIG. 2.

FIG. 5.

FIG. 3.

FIG. 4.

FIG. 6.

FIG. 7.

FIG. 8.
